Primary Examiner — Brett Miller*Assistant Examiner* — Rani J Abdallah(74) *Attorney, Agent, or Firm* — Diederiks & Whitelaw, PLC; Annette M. Frawley, Esq.(57) **CLAIM**

The ornamental design for a jar, as shown and described.

DESCRIPTION

FIG. 1 is an upper perspective view of a jar according to our new design;

FIG. 2 is front view of the jar;

FIG. 3 is a rear view of the jar;

FIG. 4 is a right view of the jar;

FIG. 5 is a left view of the jar;

FIG. 6 is a top view of the jar;

FIG. 7 is a bottom view of the jar; and,

FIG. 8 is a cross section view of the jar, taken along line 8-8 in FIG. 6.

In FIGS. 1-6 and 8, broken lines are used to disclose environment structures related to the claimed design for illustrative purposes and form no part of the claimed design. In FIGS. 1-6 and 8, broken lines are used to show exterior screw threads on the mouth of the jar for illustrative purposes only.

1 Claim, 5 Drawing Sheets(56)
